Sigmund Loewe

UNITED STATES PATENT OFFICE

SIEGMUND LOEWE, OF BERLIN, GERMANY, ASSIGNOR TO RADIO CORPORATION OF AMERICA, A CORPORATION OF DELAWARE

MULTIPLE UNIT HIGH-FREQUENCY AMPLIFIER

Application filed September 17, 1925, Serial No. 56,953, and in Germany September 23, 1924.

It has been found, that the problem of aperiodic high-frequency amplification, where the number of periods exceeds 500,000 per second, becomes with the use of vacuum tubes more and more difficult as the rate of frequency increases (see Barkhausen's "Elektronenröhren" Leipzig 1923, page 92). For these high-frequencies, however, it is absolutely necessary to have high-frequency amplifiers, because on the one hand, short wave lengths are generally used for broadcasting purposes, and on the other hand, because short wave lengths have proved especially suitable for long distance transmission.

15 The object of this invention is to provide an aperiodic high-frequency amplifier, which is effective up to very high frequencies. Repeated tests have proved that the ordinary capacity-resistance connection for high-frequency amplifiers is well suited for this purpose, provided two factors have not been left out of consideration, namely the capacities between the circuit elements and the capacities in the interior of the tube should be kept 20 as low as possible. Barkhausen has already pointed out this necessity.

On the other hand experience has proved that the resistances heretofore used for the purpose will cause certain disturbing influences, which render them unsuitable for use 25 in high-frequency amplifiers. They show certain properties, which may be termed residual voltage effects. These properties are characterized by the fact that as in the case 30 of condensers and storage batteries after a current has passed through such a resistance, a certain residual voltage will remain, and will only very slowly flow off. It is quite 35 easy to observe this surplus voltage even after the lapse of several seconds. If a resistance showing these residual properties is traversed by high frequency currents, it will 40 act like a capacity, that is its effective resistance will decrease with the increase of the 45 frequency.

The problem forming the basis for the invention could therefore be solved only by employing resistances which are completely free from any residual effect. A glass rod enclosed in a vacuum tube and coated with a 50 thin conductive coating, such as a thin layer of carbon or of soot will be especially suitable for solving this problem.

Experiments have proved that high-frequency amplifiers equipped with such resistances free from all residual charges and carefully guarded against the possibility of detrimental capacities arising will retain their full effectiveness, even up to very high 55 frequencies.

I shall further describe my invention with the aid of the accompanying drawing in which:

Figure 1 is a wiring diagram of a three 60 stage amplification system.

Figure 2 is an evacuated vessel in which, according to my invention, most of the three stage amplification system shown in Figure 1 has been incorporated.

Figure 3 is a modification thereof.

Fig. 1 represents a three-stage high-frequency amplifier produced in conformity with the invention. The tubes used are standard tubes, but without bases. These tubes are indicated by the reference numerals 1, 2 and 3. The heating filaments 4, 5 and 6 may, for instance be heated in series by a battery 7. The energy to be amplified is applied between the terminal 8 connected to the negative side of filament 4 and the terminal 21 connected to first grid 9. The first anode 10 is connected to the positive pole of a battery 12 by way of a bus for supplying positive potential and an ohmic resistance 11 of high resistance value and free of all residual effects. Furthermore the first anode 10 is connected with the grid 13 of the second tube by way of a highly insulated condenser 12'. The anode 14 of the second valve is also connected, by way of 70 75 80 85 90

the positive bus and an ohmic resistance 15 having a high resistance value and being free of any residual effects, with the positive pole of the anode battery, whence the circuit is continued by way of a condenser 16 to grid 17 of the third tube. The grids 17 and 13 are further connected, by way of a bus for supplying negative potential and like resistances 18 and 19, with the negative battery pole. The first tube or stage is connected to the second by an impedance coupling comprising the high resistances 11 and 18, and the condenser 12', and the second tube or stage is similarly connected to the third. The amplified high-frequency voltage may thus be taken off between the terminals 20. It is possible, for instance, to connect a tuned frame antenna between the terminals 8 and 21, and also by inserting a coil or other suitable coupling means between the terminals 20, the amplified high frequency voltage may be applied to a vacuum tube detector or crystal detector circuit followed by one or more stages of low-frequency amplification. It has been found, that it is possible with the help of such resistances, which are free of any residual effect in the anode circuit, as well as in the grid connections, and by avoiding the production of capacities in the tube base, to produce properly operating high-frequency-amplifiers up to wave lengths of 150 meters.

The high-frequency amplifier described above will still possess a comparatively large capacity between the several elements of the circuit. In order to reduce this capacity to a minimum, the following steps have been taken by the inventor:—

The multiple high-frequency amplifier system is enclosed within a tube, the resistances in the grid circuit and the transfer capacities being also preferably mounted within said tube. For this purpose, the resistances in the grid circuit and the capacities 12' and 16 can be enclosed in special tubes, or if necessary in vacuum tubes.

Fig. 2 shows as an example a triple or three stage amplifier, constructed according to this invention.

In a glass frame 22 the filament 24 adapted to be heated to incandescence is held in position by the insertion of a tungsten spring 23. The three grid and anode sets constituting the three stages are, as shown in this figure, arranged either on the side, or cylindrically round the glowing filament. On the frame there is further mounted a collecting wire or negative bus 25, connected with the negative pole of the heated filament. Similarly the frame carries a rod or positive bus 26 connected with the positive battery pole. The first grid is carried, for instance, through the glass bulb at 27, and the positive terminal of the filament is carried through at 28. The first anode is connected by a resistance

11, which is free of residual effects, to the positive collecting wire or bus, and by way of a capacity 12' which is preferably enclosed within an air-tight space to the second grid 13. The second grid, if desired, can also be connected by way of a resistance 18, which is absolutely free of residual effects, to the negative collecting wire. The second anode is connected correspondingly by way of a resistance 15 of the same character to the positive collecting wire, and by way of a condenser 16 which is enclosed in a vacuum to the third grid 17. The third anode is led out through the stem, while the third grid can be connected by way of a resistance 19 of the same character to the negative collecting wire 25. The surrounding glass bulb 29 encloses the whole apparatus airtight and it has altogether five sealing-in points, viz., two for the filament ends, one for the first grid, one for the third anode, and one for the positive collecting wire or bus. By means of this arrangement, it is possible to reduce the effect of the injurious capacities to such an extent that amplification of high frequencies up to 10,000,000 cycles can be obtained.

A further improvement can be obtained by the use of insulated grids. By the use of such grids, that is, a grid the surface of which is suitably screened against the reception of electrons, as for instance by the interposition of mica sheets or by coating the grid with borax or porcelain enamel, the otherwise necessary block condensers 12' and 16 can be dispensed with, as well as the resistances 18 and 19 in the grid circuits which are necessary in most cases.

An example of the construction of the system with insulated grids is shown in Fig. 3. The grids in this case are designed as control electrodes, and are not fixed between plate and cathode, but beyond the space between plate and cathode. The effect and principles of this arrangement as amplifier are well known. The heating filament is mounted as shown in Fig. 2. The first anode 40 is situated in the left hand top corner, and the first control grid 41 in the right hand top corner. It is carried out of the glass bulb just like the filament terminals. Mica plates are interposed between each of the control electrodes and the filament, said plates being either fastened on to the control electrodes, or kept freely in suspension by means of small brackets positioned in the space between filament and control electrode. For the three stages these mica plates are designated respectively 42, 43, 44. From the first anode the circuit leads by way of a resistance 45 which is free from residual effects to the positive collecting wire 26, which is also sealed into the foot of the bulb. The second stage is so arranged that the second control grid 46 is situated on the same side as

the first anode. It is connected with the latter by means of a wire, but screened from the filament by an interposed mica plate 43. The second anode 47 is connected, by way of a resistance 48, free of residual effects, to the positive collecting wire 26. The third control grid 49 is placed on the same side of the filament as the second anode and this grid is also screened from the filament by an interposed mica plate 44, and connected conductively with the second anode by a wire. The third anode 50 is separately supported and led out through the stem of the glass bulb.

15 In the manner described it will be possible to build high-frequency amplifying sets, hardly larger than the plain amplifying tubes used at present, and yet many times more effective.

20 My means of the last-described construction an effective amplification of the highest existing frequencies will be made possible. It is of course not necessary to confine oneself to a three stage construction, since a still 25 larger number of similarly constructed stages may be used.

It is further of great importance that the first stages have comparatively short lengths of the anode and the grid, as the currents in 30 the first amplifying stages are very weak. Only the subsequent stages have larger anode and control surfaces to correspond with the increase of the currents to be carried by the apparatus.

35 Frequently the problem may arise to construct such sets in a form which will permit of a low current consumption. If filaments are used which are coated with an oxide covering, there will be no difference in 40 the design used for tungsten filaments. If, however, an economy in heating current by the atomization of magnesium or similar metals in vacuum is desired, care must be taken that the deposits of metal thus produced will not provide any conductive path 45 between the different parts, which should be insulated from each other. The inventor has found that the formation of a conductive deposit between two points which should be kept insulated from each other can be avoided by protecting the points in question 50 by means of a screen either of glass, metal, or mica, which is placed in front of the places to be protected against such deposits.

55 Protective screens of this kind are used wherever it is necessary to maintain a high insulation. The deposit in this case settles on the screen, and the protected parts, which must remain insulated, will remain free of such deposits. The evacuation of these systems is best done by placing the entire tube on the pump in a high frequency eddy current field.

60 For mounting the blocking condensers in

the vacuum tubes according to Fig. 2, it will be preferable to enclose the condensers separately in airtight glass tubes. This method will do away with the necessity of having to evacuate the condenser itself. For example, 70 two copper foils separated by a strip of mica may be placed within a glass tube, said foils being rolled into a small coil. The two ends of the glass tube must be sealed, and the two leads carried out-side. This tube may 75 be freed of air, but it is quite sufficient to seal in the condenser perfectly airtight. Similarly, the degassing of the high ohmic resistances may be dispensed with by sealing them, if possible, under vacuum, into 80 glass tubes. Condensers, or resistances, enclosed in a vacuum tube in the manner described above will behave exactly like any parts of the surrounding glass surface, considered from a vacuum-technical point of 85 view.

I claim:

1. A vacuum tube adapted for multi-stage amplification, comprising an evacuated envelope, a plurality of stages contained therein, a single filament common to all the stages, a control electrode and a plate electrode for each stage, impedance coupling between successive stages, a collecting element, and a high resistance element connecting the control electrode of the last stage with the collecting element. 90

2. A vacuum tube amplifier, comprising an evacuated envelope, a plurality of stages contained therein, a single filament common to all the stages, a control electrode and a plate electrode for each stage, a blocking condenser between each grid and the plate of the preceding stage, a conducting element within the tube, a high resistance element connecting each plate with said conducting element, all of said elements mounted entirely within the tube, and external leads for the filament, conductor, first control electrode and the last plate. 95

100 3. A vacuum tube adapted for multi-stage amplification, comprising an evacuated envelope, a plurality of stages contained therein, a control electrode and a plate electrode for each stage and a common filament for all the stages, a bus adapted to supply positive potential to the plates, a high resistance element connecting each plate with said bus, a condenser connecting each grid with the plate of the preceding stage, a bus adapted to supply negative potential, a high resistance element connecting the control electrode of the last stage with the said last named bus, all of said elements being mounted entirely within the tube, and external leads for the filament, first control electrode, last plate and said buses. 115

120 4. A multi-stage vacuum tube amplifier, comprising an evacuated envelope, a plurality of resistance-coupled stages wholly con- 130

tained within said envelope, a common cathode for all said stages, grid and plate electrodes for each of the stages, external connections to both terminals of the common cathode, an external connection to the grid electrode of the first stage, another external connection common to the grid electrodes of the succeeding stages, an external connection to the plate electrode of the last stage, and another external connection common to the plate electrodes of the remaining stages.

In testimony whereof I have affixed my signature.

SIEGMUND LOEWE.
